MICROFICHE VIEWER

Paul B. Specht, Evanston, Ill., assignor to Library
Resources Inc., Chicago, Ill.

Filed Mar. 18, 1971, Ser. No. 125,916

Term of patent 14 years

Int. Cl. D16—02

U.S. Cl. D61—1

FIG. 1 is a front elevational view of a microfiche reader showing my new design;

FIG. 2 is a left side elevational view thereof;

FIG. 3 is a top plan view thereof;

FIG. 4 is a right side view of FIG. 1 on a reduced scale;

FIG. 5 is a rear elevational view of FIG. 1 on a reduced scale;

FIG. 6 is a bottom plan view of FIG. 1 on a reduced scale.

I claim:

The ornamental design for a microfiche viewer, as shown.
